UNITED STATES PATENT OFFICE.

FRANK A. PERRET, OF BROOKLYN, NEW YORK, ASSIGNOR TO THE ELEKTRON MANUFACTURING COMPANY, OF NEW YORK.

DYNAMO-ELECTRIC MACHINE.

SPECIFICATION forming part of Letters Patent No. 403,487, dated May 14, 1889.

Application filed December 29, 1888. Serial No. 294,981. (No model.)

To all whom it may concern:

Be it known that I, FRANK A. PERRET, a citizen of the United States, residing at Brooklyn, in the county of Kings and State of New York, have invented certain new and useful Improvements in Dynamo-Electric Machines; and I do hereby declare the following to be a full, clear, and exact description of the invention, such as will enable others skilled in the art to which it appertains to make and use the same.

This invention relates to improvements in the construction of dynamo-electric machines in which it is desirable to have as little machine-work as possible, and have the parts interchangeable in different machines of the same size.

The invention comprises certain improvements in the construction of field-magnet, pole-pieces, cores, and yokes from sheet-iron by stamping the parts at once to their finished form, so that they may be immediately put together and wound without further manipulation or machine-work.

The invention also comprises a means for clamping together the plates of the field-magnet and attaching them to the base of the machine, as also certain peculiarities in the form of the plates making up the field-magnet, whereby the operation of winding the same is very much facilitated.

The invention also comprises an improved way of mounting the armature in a frame which is firmly fixed to the field-magnet, so that when once put together there is no possibility of any of the parts slipping from its exact position, which is very important in machines of the laminated field type.

In the drawings which form part of this specification, Figure 1 is a side elevation of the machine as constructed in accordance with this invention. Fig. 2 is a plan view of the same on a reduced scale. Fig. 3 is an end elevation of Fig. 2 at the commutator end. Fig. 4 is a plan view of one of the plates stamped out ready for use in the field-magnet. Fig. 5 is an end view of the field-magnet when put together ready for winding. Fig. 6 is an end view of the field-magnet with its limbs swung apart by means of the jointed yoke-pieces, permitting direct winding in a

lathe after the field-magnet has been all put together otherwise. Fig. 7 is a plan view of the frame which serves to carry the armature, bind the plates of the field-magnet together, and attach the whole machine to its base. Fig. 8 is a sectional detail showing the manner of use of the standards which connect the machine to the base-board. Figs. 9 and 10 show modifications of form permitting the separate yoke-pieces to be dispensed with. Fig. 11 is an end view of the magnet so constructed. Fig. 12 is a plan of the form of section used in making larger machines. Fig. 13 is an end view of the magnet so constructed, and Fig. 14 is an elevation of the form of standard for attachment to base.

In carrying out my invention I first stamp out of a suitable gage of soft well-annealed sheet-iron a number of plates corresponding in shape to that shown in Fig. 4, having the pole-piece P with shoulders a, core-piece C, and yoke-piece Y, also having the shoulders b and the extension d. In forming these plates I punch at about the center of the pole-piece a hole, e, and in the yoke portion Y, I punch two holes, f and g, as shown in Fig. 4. The yoke-piece Y is so proportioned that when the curved faces of the pole-pieces P on the opposite sides are the proper distance apart for the insertion of the armature the inner edges of two corresponding yokes, Y, will substantially meet from their lower extremities to their centers, as shown by dotted lines in Fig. 5, from which point the edges are curved away to permit of the opening out of the two sides of the field-magnet, for the purpose of winding, as indicated at Fig. 6. I next stamp out of similar sheet-iron, but preferably a somewhat thinner gage, the supplementary yoke-pieces y of such length as to reach substantially across the yoking distance of the magnets. These pieces are plain straight bars or plates, and are formed with four holes, two of these holes, f', corresponding in size and position with the holes f in the yoke-pieces Y of the other plates, and two of the holes, g', corresponding in size and position with the inner holes, g, stamped in the inward projection of the yoke-pieces Y of the other plates.

The field-magnet may be put together con-

veniently by using pins upon which to thread the plates by means of, for instance, the holes f and f' . I first start by placing one of the plates y upon the pins, and then putting on 5 two of the plates P C Y in opposition to each other. Then I place one of the plates y and at the same time place a plain iron washer of the same thickness as the plate y on each of the pole-pieces P, the washers being conveniently held in position by temporary pins located for the purpose, and so on continuously until a proper width of field-magnet has been obtained, one of the plates y and 10 two washers alternating with every pair of magnet-plates, and the outside being finished up with one of the plates y , so that there is one of the latter at each side of the field-magnet. I then insert the bolts h through the holes f and bind the whole together with nuts. I also insert bolts i through 15 the holes g and fit these bolts also with nuts. Rods K are previously prepared, plain at their middle portion, with a screw-threaded portion, l , near each end, and beyond this formed with a shoulder, m , at each end by reducing the diameter of the pin, and at the extreme end screw-threaded for the reception of nuts. I pass one of the rods K through 20 each of the pole-pieces P, and these rods will have the threaded portions l cut so as to project somewhat beyond the limits of the pole-pieces of the machine. Before placing the 25 nuts n in position on the threaded portions l of the rods K, I slip over the latter the metal standards O, which are preferably of brass 30 and have their pin portions q screw-threaded, as shown, the intention being that the threaded portions or studs q of the standards O shall pass through the base-board of the machine, 35 and be fastened below by means of nuts, as indicated at Fig. 8, one of the standards O being placed on the rods K at each end. The nuts n are then put on and screwed home, the result being to press the plates forming the 40 field-magnet and the intervening washers solidly between the standards O, the same as if the field-magnet itself were one solid mass, and at the same time affording a most convenient means of attaching the machine to a 45 base-board of any desired character. The armature, having been previously wound and finished, is placed in its position in the circular space between the pole-pieces, and the hangers H, previously fitted for the purpose, 50 are slipped onto the ends of the armature-shaft and onto the ends of the rods K until they come against the shoulders m , and are there held firmly by means of the nuts s . The armature is thus provided with a solid bearing 55 at each end, and great facility for constructing the bearings perfectly true is afforded by this arrangement. The portions of the rods K intervening between the hangers H and the nuts n are utilized for the purpose 60 of placing the brush-holders T in a convenient and readily accessible position.

A field-magnet constructed as above set

forth can be readily wound by swinging the limbs apart—for instance, as shown in Fig. 6—and then clamping in a chuck or to a face-plate. Insulation is easily applied and the winding can be done quickly. The magnetic joint at the yoke is good and capable of carrying all lines of force set up, since the area of contact at the yoke is in all cases greater 75 than the total cross-sectional area of the core.

In some cases it is desirable to increase the cross-sectional area of the core within the same linear dimensions. I then modify the form of blank and construct it as shown in 80 Figs. 9 and 10, the two being alike in all respects save the yokes, in which, for the purpose of fastening with a single bolt at the center, I make the joint or parting-line at one side of the center, thus having on one blank 85 a short yoke-extension, d' , and on the other a correspondingly longer extension, d'' . The bolt-holes f are as before; but I use only a single hole, g , at the center. In putting together the two plates are set as in Fig. 11. 90 Then another pair is placed in reversed position, as indicated by the dotted line, showing the next joint to be on the other side of the center. After all are in position, the corner bolts, h , are placed in the holes f and nuts 95 applied to draw all into firm contact, and then the rods K are applied, as before. For winding, the two halves which thus interleave at the yoke are simply drawn apart bodily, and after winding they are brought together, and 100 a single bolt, i , is passed through the holes g and secured.

For larger machines of the consequent pole type I punch out a number of single blanks of the form shown at Fig. 12, each having the 105 complete pole-piece P, with shoulders a and two holes, e , the core C, and the complete yoke Y, having shoulders b and one hole, g . With these blanks I build up the magnet shown in Fig. 13, four plates being necessary 110 to complete the inclosure, each plate overlapping the next at either the pole-piece or the yoke, as indicated by dotted lines in Fig. 13. The frame for hanging the armature will in this case have four of the bars or rods K. 115 For winding, the magnet is drawn apart at the yokes Y after withdrawing the pins from holes g , and to prevent the plates being pressed together I insert a comb or a number of washers temporarily between the various yoke portions Y. After winding, the two halves are brought together and secured by permanent bolts, as before. In this form the standards O may to advantage be cast together into a single standard, O', through which the ends 120 of rods K will project and be secured by nuts n , as before.

It is to be observed that I do not attempt to insulate layer from layer. On the contrary, I place the iron plates in magnetic contact, as it is desirable to inclose as much iron as possible within the exciting-coils, and the scale always present on commercial sheet-iron has a sufficient electrical resistance to reduce 130

the loss by eddy-currents from plate to plate to an insignificant minimum.

I claim as my invention—

1. A dynamo-electric machine having its field-magnet built up in layers of thin plates of sheet-iron in planes at right angles to the armature-shaft, each layer composed of at least two portions connected in closed magnetic circuit at the yoke, in combination with one or more clamping-bolts, one of which serves as a pivot upon which the respective portions of the magnet can be swung apart for winding.
2. In a dynamo-electric machine, a field-magnet built up in layers of thin plates of sheet-iron, each plate constituting in one piece a pole-piece, a core, and part of the yoke, and pierced with bolt-holes, in combination with bolts passing through all the layers and holding them in rigid relation together.
3. In a dynamo-electric machine, a field-magnet built up in layers of thin plates of sheet-iron, each plate constituting in one piece a pole-piece, a core, and part of the yoke, and pierced with bolt-holes, in combination with supplementary yoke-plates, also pierced with bolt-holes and interleaved with the other plates, and bolts passing through all the plates and holding them in rigid relation together.
4. In a dynamo-electric machine, a field-magnet built up in layers composed of thin plates of sheet-iron in planes at right angles

to the armature-shaft, each plate having in one piece a pole-piece, a core, and part of the yoke, each plate on one limb being magnetically connected at the yoke to a corresponding plate on the other limb by bolts parallel with the armature-shaft, and all the plates forming one pole of the machine being secured together by bolts passing through their polar portions.

5. In a dynamo-electric machine having its pole-piece laminated and perforated with bolt-holes, the bolts or rods K, provided with nuts n, for compressing the pole-plates together, and having shoulders m, in combination with the armature-hangers H and nuts s, whereby the rods K serve to hang the armature in true alignment and prevent individual motion of the plates.

6. In a dynamo-electric machine having its pole-pieces laminated and perforated with bolt-holes, the bolts or rods K, provided with nuts n, for compressing the pole-pieces, and having shoulders m, in combination with the hangers H and one or more standards, O, secured between the nuts n and said pole-pieces.

In testimony whereof I affix my signature in presence of two witnesses.

FRANK A. PERRET.
